CLAIM

The ornamental design for a resilient fabric gift wrap, as shown and described.

DESCRIPTION

FIG. 1 is a top plan view of a resilient fabric gift wrap showing the sleeves of the giftwrap separated;

FIG. 2 is a bottom plan view thereof;

FIG. 3 is a perspective view thereof, shown in an alternate configuration of use assembled onto a gift box; and,

FIG. 4 is a side elevation view thereof.

In the drawings, the broken lines showing portions of a resilient fabric gift wrap depict environment and form no part of the claim. The surface shading shown in the drawings represents resilient fabric.
